(57) **CLAIM**

The ornamental design for a tai chi shaped charcuterie board, as shown and described.

DESCRIPTION

FIG. 1 is a front perspective view of a tai chi shaped charcuterie board showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view of the tai chi shaped charcuterie board in its closed state; and,

FIG. 10 is an enlarged view of portion 10 in FIG. 2.

The broken lines show the features of the tai chi shaped charcuterie board that form no part of the claimed design. The dash-dot-dash broken lines define the boundary of an enlarged view and form no part of the claimed design.
